UNITED STATES PATENT OFFICE.

EDGAR H. COTTRELL, OF WESTERLY, RHODE ISLAND.

METHOD OF PRODUCING PRINTED PRODUCTS.

1,170,609.

Specification of Letters Patent.

Patented Feb. 8, 1916.

Application filed April 27, 1914. Serial No. 834,661.

To all whom it may concern:

Be it known that I, EDGAR H. COTTRELL, a citizen of the United States, and resident of Westerly, in the county of Washington 5 and State of Rhode Island, have invented a new and useful Method of Producing Printed Products, of which the following is a specification.

In newspapers and other large printed 10 products of a similar character as now printed and folded parallel with the columns of printed matter, it is well known that because of the very large size of the leaves, the poor quality of the paper used, 15 and the location of the fold, it is extremely difficult to properly handle the paper because of the tendency of the free portions of the leaves above the point held at one side of the paper, to fall over. This tendency is extended to both sides of the paper when the paper is unfolded. Furthermore, 20 it is well known that when the paper is unfolded, it is extremely difficult, awkward and tiresome to properly hold the same for perusal and it is also very difficult to fold 25 back a leaf because of the tendency of a leaf to fall over by gravity in the wrong direction and because of the large size of the sheet.

30 My invention consists in the method of producing a newspaper which will be very convenient for handling and reading, the newspaper being at all times kept within a reasonable size.

35 A further object is to so print the web or webs that the associated sheets cut therefrom may be read from beginning to end by turning the leaves over successively in the same direction.

40 A further object is to fold the sheets transversely through the middle of their printed pages or to secure the sheets together transversely through the middle of their printed pages or to fold said sheets 45 together transversely through the middle of their printed pages and secure said sheets together along said fold line.

45 A still further object of my invention is to so print the web or webs and so handle 50 the same that each of certain pages will

appear entirely on one sheet and each of other pages will appear partly on one sheet and partly on another sheet.

I have chosen to show, as a practical embodiment of my invention, a machine for carrying out my method which will print and deliver a double twelve-page product from two webs.

In the accompanying drawings, Figure 1 represents a diagrammatic elevation of the machine, Figs. 2 and 2^a represent the machine in perspective from the last printing couple of the printing mechanism through to the delivery of the product, Fig. 3 represents a top plan view of a portion of the upper printed web, showing the relative arrangement of the page and page sections thereon, Fig. 4 represents a bottom plan view of a portion of the upper web showing the relative arrangement of the page sections thereon, Fig. 5 represents a top plan view of a portion of the lower web showing the relative arrangement of the page sections thereon, Fig. 6 represents a bottom plan view of a portion of the lower web 75 showing the relative arrangement of the page and page sections thereon, Fig. 7 represents a front view of the printed product in its folded position as delivered from the machine, Fig. 8 represents a front view of 80 the product in its unfolded position, the upper corners of the respective leaves being shown separated to clearly indicate the arrangement of the pages, and Fig. 9 represents a front view of the product after the 85 lower half of the front sheet has been turned over, the lower corners of the remaining sheets being turned over and separated to clearly indicate the arrangement of the pages. 90

The upper web is denoted by 1 and the lower web by 2. The upper web is led through a perfecting printing mechanism comprising the printing couple 3, 4, for printing on one side of the web, and the printing couple 5, 6, for printing on the other side of the web. The lower web 2 is led through a perfecting printing mechanism comprising the printing couple 7, 8, for printing on one side of the web, and the 100

printing couple 9, 10, for printing on the other side of the web. The printing mechanisms which act upon the upper and lower webs are so arranged that they will print 5 the front and back pages of the newspaper at different points on the webs and the intermediate pages each partly at one point and partly at another point on the webs. In the present arrangement, the upper side 10 of one portion of the upper web transversely across the same, will bear page 1, the upper halves of pages 11 and 9, and the lower halves of pages 3 and 5. The lower side of this portion of the upper web will 15 bear, respectively, transversely across the web, the upper halves of pages 2, 4 and 6, and the lower halves of pages 12, 10 and 8. The corresponding portion of the upper side of the lower web will bear transversely 20 across the same, respectively, the upper halves of pages 12, 10 and 8, and the lower halves of pages 2, 4 and 6. The under side of the said portion of the lower web will bear, transversely across the same, respectively, 25 the upper halves of pages 3 and 5, the lower halves of pages 11 and 9, and all of page 7. The webs are here shown as three pages wide and the two webs are brought together as they pass over the roller 11 from 30 whence they pass together through the slitting mechanism 12, 13, where the associated upper and lower webs are slit longitudinally into three pairs of narrow webs. From thence these narrow webs pass over formers 35 14, 15, 16, of the web associating mechanism. From these formers 14, 15, 16, the webs are passed between their respective pairs of rolls 17, 18 and 19, and from thence over the three series of rolls 20, 21, 40 22, to the pair of rolls 23, where the three pairs of roll webs are associated together. The three pairs of associated narrow webs are then passed through the cutting mechanism 24 where the webs are cut transversely 45 into sheets. These sheets pass through guides 25 to a folding cylinder 26 from which the sheets are folded off by the blades 27 through the rolls 28 to the rotary carrier 29 which deposits the folded product upon 50 the endless delivery carrier 30.

The means which I have shown for securing the sheets together transversely across the middle of their printed pages comprises a pasting mechanism 31 arranged 55 to apply paste to one side of the lower web 2 transversely along the line between the upper halves of pages 12, 10 and 8, and the lower halves of pages 2, 4 and 6; a pasting mechanism 32 which is arranged to apply paste transversely along the line between the upper half of page 3 and the lower half of page 11 after the pair of wide webs have been separated into the three narrow webs; and the pasting mechanism 33

arranged to apply paste transversely along 65 the line between the upper half of page 9 and the lower half of page 5 after the pair of upper and lower wide webs have been separated into the three narrow webs. This arrangement of the pasting mechanisms will 70 insure the securing of the six sheets together transversely through the middle of their printed pages without the application of paste to the front or back of the product. 75

If it is desired to secure the sheets together in groups so that each group may be readily separated from the remaining group or groups, it is only necessary to vary the arrangement and number of the pasting mechanisms. The groups of secured sheets may then be folded together as above described. 80

The product produced by my method will have its front page printed on the front 85 side of one sheet, its back page printed on the back side of the back sheet and the intermediate pages each printed partly on one sheet and partly on another sheet. To permit the product to be read from beginning to end by turning the leaves over successively in the same direction, the printing mechanism and associating mechanism are arranged so that the printed matter on the front sides of all of the sheets will read in 90 one direction and the printed matter on the back sides of all of the sheets will read in the reverse direction thus causing the last page to be printed in the reverse direction to the first page and the upper half of each 100 intermediate page to be printed in the reverse direction to the first page and the upper half of each intermediate page to be printed in the reverse direction to the lower half of said page. 105

By the terms "front" page and "back" page, I mean the pages which are located respectively on the front side of the front sheet and the back side of the back sheet of the associated sheets before they are folded 110 together. Similarly, where I refer to the front and back sides of the sheets I mean before the sheets are folded.

It is to be understood that any suitable driving mechanism may be used for driving 115 the several parts of the machine so as to insure the proper printing, associating, securing and folding of the product. I have, therefore, not shown such driving mechanism herein as it is well understood in the 120 art.

While I have shown and described my method in connection with a machine which is designed to produce a double twelve-page product from two webs, it is to be understood that I do not wish to limit myself to the method of producing a product of any particular number of pages as it is obvious 125

that my invention contemplates the method of producing a product of any desired number of pages. Also, while I have shown a product as produced from two webs, it is to be understood that the products contemplated, may be produced from one or more webs, as desired. Also, while I have shown and described the folding of the product transversely across the middle of its printed 10 pages and the securing of the product along said fold line, it is obvious that I may use either one or both of these methods as desired without departing from the spirit and scope of my invention.

15 What I claim is:—

1. The herein described method of producing a newspaper consisting in printing a web so that one page of the newspaper will appear on one sheet, another page on another 20 sheet, and the remaining pages will each appear partly on one sheet and partly on another sheet, slitting the web into narrow webs, associating the narrow webs and cutting the so associated narrow webs transversely into sheets.

2. The herein described method of producing a newspaper consisting in printing a web so that one page of the newspaper will appear on one sheet, another page on another sheet, and the remaining pages will each appear partly on one sheet and partly on another sheet, slitting the web into narrow webs, associating the narrow webs, cutting the so associated narrow webs transversely into sheets and folding the sheets transversely across the middle of their printed 30 pages.

3. The herein described method of producing a newspaper consisting in printing a web so that one page of the printed product will appear on one sheet, another page on another sheet and the remaining pages will each appear partly on one sheet and partly on another sheet, slitting the web into narrow webs, securing the webs together transversely across the middle of the printed 40 pages, associating the webs and cutting the so associated webs transversely into sheets.

4. The herein described method of producing a newspaper consisting in printing a web so that one page of the printed product will appear on one sheet, another page on another sheet and the remaining pages will each appear partly on one sheet and partly on another sheet, slitting the web into narrow webs, securing the webs together transversely across the middle of the printed 50 pages, associating the webs, cutting the so associated webs transversely into sheets, and folding the sheets transversely across the middle of their printed pages.

5. The herein described method of producing a newspaper, consisting in printing a web so that the front page of the news-

paper will appear on one sheet, the back 65 page on another sheet and the remaining pages each partly on one sheet and partly on another sheet, the printed matter on the front sides of all of the sheets reading in one direction and the printed matter on the back 70 sides of all of the sheets reading in the reverse direction, whereby the newspaper may be read from beginning to end by turning the leaves over successively in the same direction, slitting the web into narrow webs, 75 associating the narrow webs and cutting the so associated narrow webs transversely into sheets.

6. The herein described method of producing a newspaper, consisting in printing 80 a web so that the front page of the newspaper will appear on one sheet, the back page on another sheet and the remaining pages each partly on one sheet and partly on another sheet, the printed matter on the 85 front sides of all of the sheets reading in one direction and the printed matter on the back sides of all of the sheets reading in the reverse direction, whereby the newspaper may be read from beginning to end by turning the leaves over successively in the same direction, slitting the web into narrow webs, 90 associating the narrow webs, cutting the so associated narrow webs transversely into sheets, and folding the sheets transversely 95 across the middle of their printed pages.

7. The herein described method of producing a newspaper, consisting in printing a web so that the front page of the newspaper will appear on one sheet, the back 100 page on another sheet and the remaining pages each partly on one sheet and partly on another sheet, the printed matter on the front sides of all of the sheets reading in one direction and the printed matter on the 105 back sides of all of the sheets reading in the reverse direction, whereby the newspaper may be read from beginning to end by turning the leaves over successively in the same direction, slitting the web into narrow webs, 110 securing the webs together transversely across the middle of their printed pages, associating the webs and cutting the so associated webs transversely into sheets.

8. The herein described method of producing a newspaper, consisting in printing 115 a web so that the front page of the newspaper will appear on one sheet, the back page on another sheet and the remaining pages each partly on one sheet and partly on another sheet, the printed matter on the front sides of all of the sheets reading in one direction and the printed matter on the back sides of all of the sheets reading in the reverse direction, whereby the newspaper 120 may be read from beginning to end by turning the leaves over successively in the same direction, slitting the web into narrow webs, 125

securing the webs together transversely across the middle of their printed pages, associating the webs, cutting the so associated webs transversely into sheets, and folding 5 the sheets transversely across the middle of their printed pages.

9. The herein described method of producing a newspaper, consisting in feeding two webs to two printing mechanisms where 10 the printing is so arranged that one page of the printed product will appear on one sheet, another page on another sheet and the intermediate pages will each appear partly on one sheet and partly on another sheet, associating the two webs, slitting the 15 two webs into a plurality of pairs of narrow webs and cutting the associated pairs of narrow webs transversely into sheets.

10. The herein described method of producing a newspaper, consisting in feeding two webs to two printing mechanisms where, the printing is so arranged that one page of the printed product will appear on one sheet, another page on another sheet 20 and the intermediate pages will each appear partly on one sheet and partly on another sheet, associating the two webs, slitting the two webs into a plurality of pairs of narrow webs, cutting the associated pairs of narrow webs 25 transversely into sheets, and folding the sheets together transversely across the middle of their printed pages.

11. The herein described method of producing a newspaper, consisting in feeding two webs to two printing mechanisms where 30 the printing is so arranged that one page of the printed product will appear on one sheet, another upon another sheet and the intermediate pages will appear each partly on one sheet and partly on another sheet, associating the two webs, slitting the two webs into a plurality of narrow webs, securing the webs together transversely across the middle 35 of their printed pages and cutting the so associated pair of narrow webs transversely into sheets.

12. The herein described method of producing a newspaper, consisting in feeding two webs to two printing mechanisms where 40 the printing is so arranged that one page of the printed product will appear on one sheet, another upon another sheet and the intermediate pages will appear each partly on one sheet and partly on another sheet, 45 associating the two webs, slitting the two webs into a plurality of narrow webs, securing the webs together transversely across the middle of their printed pages, cutting the so associated pair of narrow webs 50 transversely into sheets, and folding the sheets together transversely across the middle of their printed pages.

13. The herein described method of producing a newspaper, consisting in feeding

two webs to two printing mechanisms where 65 the printing is so arranged that the front page of the newspaper will appear on one sheet, the back page upon another sheet and the intermediate pages each partly on one sheet and partly on another sheet, associating the two webs, slitting the two webs 70 into a plurality of pairs of narrow webs and cutting the associated pairs of narrow webs transversely into sheets.

14. The herein described method of producing a newspaper, consisting in feeding two webs to two printing mechanisms where the printing is so arranged that the front page of the newspaper will appear on one sheet, the back page upon another sheet 80 and the intermediate pages each partly on one sheet and partly on another sheet, associating the two webs, slitting the two webs into a plurality of pairs of narrow webs, cutting the associated pairs of narrow webs 85 transversely into sheets, and folding the sheets together transversely across the middle of their printed pages.

15. The herein described method of producing a newspaper consisting in feeding two webs to two printing mechanisms where 90 the printing is so arranged that the front page of the printed product will appear on one sheet, the back page upon another sheet and the intermediate pages each partly on one sheet and partly on another sheet, associating the two webs, slitting the two webs into a plurality of pairs of narrow webs, securing the webs together transversely across the middle of the printed pages and 95 cutting the associated pairs of narrow webs transversely into sheets.

16. The herein described method of producing a newspaper, consisting in feeding two webs to two printing mechanisms where 100 the printing is so arranged that the front page of the printed product will appear on one sheet, the back page upon another sheet and the intermediate pages each partly on one sheet and partly on another sheet, associating the two webs, slitting the two webs into a plurality of pairs of narrow webs, securing the webs together transversely across the middle of the printed pages, cutting the associated pairs of narrow webs 105 into sheets, and folding the sheets together transversely across the middle of their printed pages.

17. The herein described method of producing a newspaper having separate groups 110 of sheets, consisting in combining a plurality of printed webs, cutting sheets transversely therefrom and securing certain of the webs together transversely through the middle of the printed pages, whereby the 115 sheets will be secured together in groups.

18. The herein described method of producing a newspaper having separate groups

of sheets, consisting in combining a plurality of printed webs, cutting sheets transversely therefrom, securing certain of the webs together transversely through the middle of the printed pages, whereby the sheets will be secured together in groups, and folding said groups of sheets together.

In testimony that I claim the foregoing as

my invention, I have signed my name in presence of two witnesses, this twenty-third 10 day of April 1914.

EDGAR H. COTTRELL.
